CLOCK

Leendert Prins, Flushing, N. Y.

Application March 8, 1938, Serial No. 194,650

2 Claims.

(Cl. 88—24)

This invention relates to clocks, and the primary object of the present invention is to provide a clock having means for projecting enlarged images of the clock hands and printed characters corresponding to the numbers of the clock dial, onto a wall or suitable surface, whereby the time may be readily told in a place or room with reduced lighting and from a material distance from the clock.

10 An important object of the present invention is to provide a clock of the above character which is simple in construction, economical to manufacture, and efficient in use.

15 A further important object of the present invention is to provide a clock of the above character including a clock proper of the type disclosed in my pending application for United States Letters Patent Ser. No. 140,040, filed April 30, 1937 and projecting apparatus readily attachable to 20 or removable from such clock proper, whereby the latter may be used alone in the ordinary way or in connection with the projecting apparatus.

With the above general objects in view, and others that will become apparent as the nature 25 of the invention is better understood, such invention consists in the novel form, combination and arrangement of parts hereinafter more fully described, shown in the accompanying drawings and claimed.

30 In the drawings:

Figure 1 is a view partly in side elevation and partly in vertical longitudinal section, of a clock with projecting means, constructed in accordance with the present invention.

35 Figure 2 is a front elevational view of the construction shown in Figure 1, with parts removed.

Figure 3 is a rear elevational view of the false-dial holder and focusing lens support forming part of the construction shown in Figure 1.

40 Figure 4 is a view somewhat similar to Figure 1 of a modified form of the invention; and

Figure 5 is a fragmentary view illustrating a mirror attachment for the focusing lens of the clock shown in Figure 1 or Figure 4, whereby the 45 images may be projected onto the ceiling or other overhead surface.

Referring in detail to the drawings, the form 50 of the invention illustrated in Figures 1 to 3 inclusive embodies a clock proper of the type disclosed in my above-mentioned co-pending application, which clock proper includes an opaque casing member 5 provided with opposed front and rear openings 6 and 7 closed by transparent members 8 and 9. The transparent member 9 closing 55 the rear opening 7 is provided with a circular

series of hour designating numerals 10 and constitutes the dial of the clock proper. Circular transparent members 11 and 12, respectively having the hour hand 13 and the minute hand 14 applied thereto and movable therewith, are located within the casing member 5 and supported for rotation within the latter by means such as grooved wheels 15 rotatably mounted in the casing member 5 at the top and sides of the latter, and driving gears 16 and 17 mounted in a hollow 10 base 18 upon which the casing member 5 is mounted, the edges of the circular members 11 and 12 engaging in the grooves of the wheels 15 so as to be guided by the latter. The circular members 11 and 12 rest upon the gears 16 and 17 15 and are formed with peripheral teeth 11a and 12a respectively meshing with the teeth of the gears 16 and 17. The circular hand carrying members 11 and 12 are located with their faces between the openings 6 and 7 and the transparent members 20 8 and 9, and means is located in the base 18 of the casing including gears 16 and 17 to rotatably drive the circular members 11 and 12 at different speeds so that the hour hand 13 carried by the member 11 is caused to traverse the dial once 25 every twelve hours, and so that the minute hand 14 carried by the circular member 12 is caused to traverse the dial once every hour. This driving means may consist of a suitable electric motor 19 connected by a train of gearings with a driven 30 gear 21 as fully shown and described in my afore-said co-pending application.

In accordance with the present invention, projecting apparatus is provided for use in connection with the clock proper, such projection apparatus including a lantern 22 seated at the forward portion of its bottom upon a shoulder 23 afforded by the base 18 at the bottom and at the rear of the casing member 5, the top of the lantern casing having a forward extension 24 provided with a downturned forward edge 25 arranged to hook over the top of the casing member 5, so as to removably hold the lantern in place upon the clock proper. Of course, any suitable means may be provided for retaining the lantern in place, and such lantern also preferably includes an insulating base 26 fixed upon the bottom of the lantern casing and carrying a socket 27 in which is placed the base of lamp 28 constituting the source of light of the lantern. A 50 suitable reflector 29 is mounted in back of lamp 28, and the lantern casing has top and bottom ventilating openings 30 and 31 provided with suitable guards 32 and 33 which permit the free circulation of air but prevent outward passage of 55

light from the lantern casing. The insulating base 26 is provided with suitable female contacts 34 which are connected as at 35 with the contacts of lamp socket 27 and which open through the bottom of the forward portion of insulating base 26 where the latter overlies the shoulder 24 of the clock base 18. At this shoulder 23, the clock base 18 is provided with upwardly projecting contact pins 36 arranged to enter the female contacts 34 when the lantern is placed upon the clock proper in the position clearly shown in Figure 1, thereby affording electrical connection of the lamp socket 27 with the source of electricity. For this purpose, the wires 37 are extended to the male contact pins 36 from the lead wire 38 which extends into the base 18 and connects with the terminals of motor 19 which drives the clock movement. Thus, the lamp 28 is connected with a source of current when applied to the clock 20 so that lamp 28 is lighted for providing the necessary illumination.

The present invention contemplates projecting the images of characters corresponding to the characters of the clock dial, but placed upon a false-dial plate 39 to afford a false-dial smaller than the actual dial of the clock, as shown at 40 in Figure 3. The central portion of this false-dial plate 39 is left transparent and provided about the margin of the transparent central portion was the dial characters or numerals 40, the remaining surrounding portion of the false-dial plate 39 being opaque as indicated by the shading in Figure 3. This use of a smaller false-dial enables the use of projecting apparatus of small size so as to minimize expense and keep the construction small and light in weight, as well as in proper proportions to the size of the clock proper. This false-dial plate 39 is suitably secured upon the rear face of an enlarged head 41 provided on the rear or inner end of a barrel 42 for supporting an adjustable focusing lens unit 43, the rear or inner end of the unit 43 being adjustably received in the bore of the barrel 42 as shown. Obviously, the adjustment of focusing lens unit 43 provides for projecting the images in sharp silhouette upon the wall or other surface, according to the size of the images and the distance of the wall or other surface from the clock. The head 41 of barrel 42 is removably fitted in the opening 6 of clock casing member 5 in front of the front closure plate 8, thereby positioning the false-dial plate 39 directly in front of the closure plate 8 with the transparent central portion of false-dial plate 39 centrally disposed with respect to the bore of barrel 42 and the hand carrying members 11 and 12. In projecting the images of the clock hands, only the inner portions of said hands are used in connection with the false-dial, suitable spaces being provided between the inner and outer portions of said hands as shown at 44 in Figure 2. In other words, images of the inner portions of the hands, only, are projected, the outer portions of the hands being outwardly of the transparent zone or central portion of the false-dial plate 39. The adjustable focusing lens unit 43 is of conventional form and forms no part of the present invention, per se. It will of course be understood that the characters or numerals 40 of the false-dial provided at 40 on the false-dial plate 39 must of course be inverted as shown in Figure 3 so that they will properly appear on the wall or other surface when projected. Direct and reflected rays of light from lamp 28 pass through the transparent members 8, 9, 11 and 12,

as well as through the transparent central portion of false-dial plate 39, thereby projecting images of the numerals 40 and the inner portions of hands 13 and 14 onto the wall or other surface, such images being greatly enlarged so as to be clearly visible from a distance and in a dark place or room. In this way, I provide a novel time-piece which is not only interesting, but useful. In order to facilitate proper position of the head 41 with respect to the casing member 5 so that the inverted numeral number 8 on the false-dial of plate 39 will be disposed at the top, the casing member 5 may be provided with a projection 45 adapted for reception within a recess or notch 46 provided in the head 41.

In the embodiment illustrated in Figure 4, the clock embodies a horizontal tubular casing 50 mounted upon a base or standard 51 enclosed at its rear or inner end as at 52, a transparent plate 53 being provided as a closure for the front end of casing section 50 and having the usual hour-designating numerals arranged on the margin thereof so as to constitute the clock dial. Arranged in the rear end of casing 50 is a suitable clock movement generally illustrated at 54, and this clock movement has a forwardly projecting elongated hollow or tubular hour hand arbor or shaft 55 that extends to a point adjacent the dial plate 53. Also projecting forwardly from the clock mechanism or movement 54 is a minute hand shaft 56 that extends through the hour hand shaft 55 and projects slightly beyond the forward end of the latter. The forward ends of shafts 55 and 56 respectively provided with the hour hand 57 and the minute hand 58.

A suitable reflector 61 is arranged between the lamps 60 and the clock mechanism 54 for projecting rays of light from lamps 60 forwardly through the dial plate 53. Any suitable means may be provided for facilitating connection of the lamps 60 with a source of electricity, and the clock mechanism 54 may be of either the electrical or mechanical type. Fitted over the forward end of casing 50 is the enlarged rear or inner end portion 62 of a barrel 63 adjustably receiving the inner end portion of an adjustable focusing lens unit 64. It will be seen that when lamps 60 are lighted, the rays of light will be projected forwardly, images of the numerals on dial plate 53 and of the hour and minute hands 57 and 58 being projected onto the wall or other surface, and such images being greatly enlarged and sharply defined by proper adjustment of the focusing lens unit 64.

Either form of the invention may be utilized to project the images of the dial and hands of the clock onto a ceiling or overhead surface by simply utilizing a reflector attachment for the outer end of the focusing lens unit 43 or 64 as illustrated in Figure 5. This reflector attachment simply consists of a sleeve 65 removably fitted over the outer end of the focusing lens unit and having an angularly disposed mirror 66 arranged to be supported at an inclination beyond the forward end of the unit 43 or 64 so as to reflect the images of the clock dial and hands upwardly onto the ceiling, overhead surface, or wall at one side of the clock. Of course, the clock of Figure 4 may be used alone or without projecting means, the dial plate 53 being placed right side up so as to secure proper disposition of the images of its numerals when projected onto a ceiling. On the other hand, when the reflecting attachment 66 is used to reflect images of the clock dial and hands onto a wall at one side of the clock, the

dial plate 53 will have to be placed up-side down. These facts will be readily understood and appreciated by those skilled in the art.

From the foregoing description, it is believed that the construction and operation as well as the advantages of the present invention will be readily understood and appreciated by those skilled in the art. Although the invention has been described in considerable detail with respect to two different embodiments, it is to be understood that the invention is susceptible of further modifications and changes in details of construction without departing from the spirit and scope of the invention as claimed.

15 What I claim as new is:

1. In combination with a clock having a base containing clock mechanism and a casing member rigid with the top of said base and having front and rear openings, transparent hand carrying elements arranged in said casing member and operated by said clock mechanism, a transparent dial in the front of said casing member and provided with opaque hour designating numerals associated with the hands of said hand carrying elements, a light projecting lantern mounted on the base at the rear of said casing member behind said hand carrying elements and said dial, an adjustable focusing lens unit removably carried by and arranged at the front of said casing member, a barrel removably fitted in the front of said casing member and supporting

said focusing lens unit, and a false-dial plate carried by said barrel and arranged in front of said hand carrying elements and said first-named dial, said false-dial plate having a restricted transparent central portion provided with opaque hour designating numerals, the hands of said transparent hand carrying elements including inner and outer separated portions, whereby enlarged images of the inner portions of said hands and the hour designating numerals on said false-dial plate may be projected onto a screen. 10

2. In combination with a clock having a base containing clock mechanism and a casing member rigid with the top of said base and having front and rear openings, transparent hand carrying elements arranged in said casing member and operated by said clock mechanism, a transparent dial in the front of said casing member and provided with opaque hour designating numerals associated with the hands of said hand carrying elements, a light projecting lantern mounted on the base at the rear of said casing member behind said hand carrying elements and said dial, an adjustable focusing lens unit removably carried by and arranged at the front of said casing member, said projecting lantern including a source of light, and cooperating contacts carried by the lantern and the base to connect said source of light with a source of current upon placing the lantern upon the clock base. 15 20 25 30
